United States Patent Office

Des. 196,180
Patented Sept. 3, 1963

196,180

GAME BOARD

Joseph L. Hvizdash, N. Main St., North Uxbridge, Mass.

Filed Mar. 18, 1960, Ser. No. 59,782

Term of patent 14 years

(Cl. D34—5)

Fig. 1

FIG. 1 is a plan view of a game board showing my new design; and

FIG. 2 is an edge view thereof.

The dominant features of my design reside in the portions shown in full lines.

I claim:

The ornamental design for a game board, as shown and described.
